HEATING AND VENTILATING APPARATUS.

No. 324,106.

Patented Aug. 11, 1885.

UNITED STATES PATENT OFFICE.

JOHN L. HAMILTON, OF ST. JOSEPH, MISSOURI.

HEATING AND VENTILATING APPARATUS.

SPECIFICATION forming part of Letters Patent No. 324,106, dated August 11, 1885.

Application filed February 25, 1885. (No model.)

To all whom it may concern:

Be it known that I, JOHN LINTON HAMILTON, of St. Joseph, in the county of Buchanan and State of Missouri, have invented certain 5 new and useful Improvements in Heating and Ventilating Apparatus, of which the following is a full, clear, and exact description.

The object of my invention is to provide a simple, inexpensive, and effective system of 10 heating and ventilating lower and upper rooms by the agency of a fire on the hearth in the lower room.

The invention consists in the peculiar construction and arrangement of hot-air flues and 15 passages, air-chambers, and ventilating flues with a fire-place in the lower room and its smoke-flue, all as hereinafter fully described and claimed.

Reference is to be had to the accompanying 20 drawings, forming part of this specification, in which similar letters of reference indicate corresponding parts in all the figures.

Figure 1 is a perspective view of my improved heating and ventilating apparatus as 25 applied to heat two rooms, one above the other. Fig. 2 is a vertical sectional side elevation of the same. Fig. 3 is an enlarged front sectional elevation, partly broken away. Fig. 4 is an enlarged side elevation, partly broken away, 30 and in section on the line *x x*, Fig. 3, and Fig. 5 is a sectional plan view taken on the line *y y*, Fig. 3, and partly broken away.

The letter A indicates a fire-place shown 35 without a grate; but it may have a grate fitted in it, if desired. At B is shown a hood fitted tightly over the fire-place and at the lower end of an air flue or chamber, C, which extends upward through the lower room, D, to the close horizontal partition or wall E, which 40 is about on a level with the floor of the upper room of the building.

A smoke-flue, F, leads from the hood B up 45 through the air-chamber C and partition E, and through an air-chamber, G, opening at *g* into the upper room H, and the flue F passes also through the partition I, forming the top 50 of chamber G, into an upper smoke-flue, J, which extends through the roof to receive a chimney top or cap of any approved design. The hot-air outlet *g* may be covered by a screen, K, of any suitable character.

The fire-place A is peculiarly constructed

as follows: I make its exposed back and end walls of common or fire-clay bricks *a* and hollow cast-metal chambers *a'*, preferably of like 55 size with the bricks *a*, and open at their backs, said chambers *a'* being made preferably of cast-iron one-fourth of an inch thick, and laid in the fire-place walls end to end, and alternately with the bricks *a*. Between every layer 60 of bricks *a* and metal chambers *a'*, I set the metal plates L, which range horizontally around the fire-place and cross a space, M, about four inches (more or less) in width, and the outer parts or edges of the plates L are set into the 65 common hard-brick wall N back of the space M. The ends of every alternate plate L at the opposite sides and front of the fire-place are cut away at the space M, as at *l*, and an air-inlet, O, is provided at one side of the fire- 70 place front next the floor. With this construction the space M is divided vertically by the plates L into a series of smaller chambers, *m*, opening into each other alternately at the front of the fire-place at both sides, so 75 that cold air entering at O will pass around one chamber *m* to the opposite or left side and front of the fire-place to escape at *l* into the next higher chamber *m*, and will travel back through this chamber to escape at the 80 right side of the fire-place into the next higher chamber, and so on, the air passing entirely around the fire-place as it rises to each successively higher chamber *m* of the series, and from the upper chamber *m*, and preferably 85 at or near the center of the back wall of the fire-place, the air admitted at O, now thoroughly heated, will enter a flue, P, which ranges upward and opens at *p* into the upper 90 hot-air chamber, G, and pass to the upper room, H, for heating it, the fire in the fire-place A thus serving to heat both rooms D and H, the flue F giving off heat directly to room H, where it passes through the air-chamber G.

It is evident that the hollow metal chambers *a'* readily take up the heat from the fire in fire-place A and give it off to the circuitous chambers *m*, and as many of these chambers *a'* will be used as the weight of the upper flue-walls will allow, so as to secure maximum heating effect on the air passing to the upper room, H.

The passage of the smoke-flue F through

the chamber C heats the air therein, and to utilize this heat for warming the lower room, D, I make lower and upper passages, Q R, from the chamber C to the room, through 5 which the air of the room may circulate.

In the smoke-flue F is pivoted the damper f, the stem f' of which passes outward through one of the passages Q R, preferably the upper one, R, as shown, and has suitable connecting-rods, s S, with any suitable detents, allowing the damper f to be set for controlling the draft of the fire on the hearth.

The lower room, D, will be ventilated directly through the fire-place A and flue F, 15 and for ventilating the upper room, H, I provide an air-flue, T, which ranges through the hot wall at the side of the hot-air and smoke flues G J, so that an upward draft is induced in said flue T, which has an opening at t into 20 room H, near the floor, and an upper opening at t', communicating with the flue J, and also with the room H near the ceiling, and the openings t t' have any suitable registers or 25 valves, U V, respectively fitted to them in room H, either of which may be opened to ventilate the room into flue J from the top or bottom, as may be preferred.

At W is shown a cap covering an opening, w, into the upper smoke flue, J, which cap 30 may be removed for cleaning out the soot from the flue J, as may be required.

Any suitable pipe receiving air from outside the building may connect with the air-inlet O or passage m, so that pure warmed 35 air may be supplied to the upper room, H, instead of admitting the air directly from the lower room through the inlet O, as will readily be understood.

I may make the hollow air-chambers a', 40 built in the fire-place wall, of material other than cast metal, the object being to secure by said thin chambers the quick continuous passage or radiation of heat from the fire-place to the air-passage m around it.

45 In building the fire-place A into a wall where it has to support considerable weight of superstructure, the hollow chambers a' and solid brick a will be built up in columns, so that the columns of brick a will sustain the 50 weight, and without danger of crushing the hollow chambers a'.

It is evident that the flue P may consist of a common stove-pipe run up through or alongside of chamber C, instead of being built into 55 the wall, as shown, and when such a pipe-flue is used it will give off considerable heat to the

chamber C, for distribution to the lower room through the openings Q R.

Having thus described my invention, what I claim as new, and desire to secure by Letters 50 Patent, is—

1. In heating and ventilating apparatus, the fire-place A, built with hollow walls forming an air-space, M, a series of plates, L, set across space M and cut away alternately at the ends 65 to form a circuitous passage, m, provided with an air-inlet, and the exposed wall of the fire-place provided with hollow air-chambers a', substantially as herein set forth.

2. In heating and ventilating apparatus, the 70 combination, with the fire-place A, constructed with hollow walls forming an air-space, M, a series of plates, L, set across space M and cut away alternately to form a circuitous passage, m, having a cold-air inlet, and the air-chamber 75 a', built in the fire-place wall of the air-flue P, communicating with passage m, and leading to an upper room to discharge hot air therein, substantially as herein set forth.

3. In heating and ventilating apparatus, the 80 combination, with the fire-place A, built with hollow walls forming an air-space, M, a series of plates, L, set across space M and cut away alternately to form a circuitous passage, m, having a cold-air inlet, an air-flue, P, leading 85 upward from passage m, an air-chamber, G, in the upper room, into which the flue P discharges the hot air, and the smoke-flue F, leading from the fire-place A and passing through chamber G, whereby the air escaping 90 from passage m is further heated by the flue F on its way to room H, substantially as herein set forth.

4. In heating and ventilating apparatus, the combination, with the fire-place A, hood B, 95 fixed therein, and smoke-flue F, of the air-chamber C, inclosing flue F above the fire-place, and the hot-air-circulation passages Q R, arranged one above the other in the side wall of said chamber, connecting it with the 100 lower room, substantially as herein set forth.

5. In heating and ventilating apparatus, the 105 ventilating-flue T, made in the heated wall along the hot-air chamber G and smoke-flue J, and communicating by the lower passage, t, with the upper room, H, and by upper passage, t', with room H and flue J, substantially as herein set forth.

JOHN L. HAMILTON.
